UNITED STATES PATENT OFFICE.

PHILIP HOGAN, OF ST. LOUIS, MISSOURI.

SEAM CLAMP.

Application filed April 4, 1924. Serial No. 704,293.

My invention relates to the suspension or carrying of cables, conduits and the like upon the sides of brick or other masonry walls and consists in a spring member adapted to be inserted in a wall seam and there distorted and held by friction. Such devices are commonly known to the trade as seam anchors or clamps.

The main object of my invention is to provide a simple inexpensive member adapted to be inserted easily in a seam in a wall and to securely hold a cable or the like against the wall.

An additional object of my invention is to provide means cooperating with such a clamp for attaching individual lines or smaller cables without affecting the design or use of the main clamp member.

In the accompanying drawings which illustrate my invention—

Figure 1 is a side elevation of a clamp applied to a wall and before the cable is inserted therein.

Figure 2 is a similar elevation of the clamp holding a cable and also illustrates the additional wire carrying member.

Figure 3 is a front elevation of the parts illustrated in Figure 2.

Figure 4 illustrates a modified construction.

Figure 5 illustrates the supplementary element applied to the clamp shown in Figure 4.

In Figure 1, A and B represent two bricks, the space C between which is normally filled with mortar which is removed at intervals for the reception of the seam clamp. The clamp is preferably formed of a single strip of material possessing some springiness and is C-shaped having a portion adapted to be inserted in the seam C, the end 1 of which portion engages the upper face of the seam and the curved part 2 of the inserted portion engages the lower face of the seam. The opposite end 1^a of the clamp terminates adjacent to the outer face of the wall and at a point spaced vertically from the seam. It will be understood that the clamp is distorted when in the position illustrated in Figure 1 and that the tendency of the clamp is to press the upper end 1^a against the outer face of the wall. When a cable D is inserted between the outer end of the clamp and the wall, the clamp is further distorted and whether in the position shown in Figure 1 or in the position shown

in Figure 2, it will be seen that there is a three-point frictional contact between the clamp and the wall provided by the shape and elastic nature of the clamp.

In the preferred embodiment of my invention the clamp is formed of a flat strap, a portion of the metal of which is displaced as indicated to provide a slot 4 and a flange 3. This construction permits the insertion of a screw driver E or similar tool as shown in Figure 1 for the purpose of bending the clamp outwardly to permit the insertion of the cable D.

The supplementary element consists in a lighter strip 5, also of spring material, and of a length which adapts one end 6 to be inserted in the crevice between the curved lower portion 2 of the clamp and the upper face of brick B and permits the other end 7, shouldered as indicated, to be inserted through a perforation 8 in flange 3. The tendency of element 5 when distorted is to straighten out, which tendency forces the two ends in opposite directions against their holding elements and securely retains the wire F in place.

In Figure 4 I illustrate a modified construction in which the anchor consists in a piece of wire 9 of spring material, the upper end of which terminates in a return bend 10 adapted to be engaged by the screw-driver or other tool as shown to move the upper portion of the clamp away from the wall and permit the insertion of the cable.

The supplementary member 11 to be applied to clamp 9 may be either flat or round and its upper end is adapted to engage the upper end of clamp 9. If member 11 is flat, its upper end may be slotted or, if round, the upper end may be flattened and perforated, or it may form a coil to surround the clamp.

Various other modifications of my invention may be made without departing from the spirit of my invention as expressed in the appended claims.

I claim:

1. A cable or like support for insertion in a wall seam comprising a C-shaped strap of spring material, the distortion of a portion of which frictionally holds the strap in a wall seam, said strap being provided with a tool receiving slot spaced from its ends, and a tool fulcrum element adjacent said slot.

2. A cable or like support for insertion in

- a wall seam comprising a strap of spring material adapted when distorted to provide spaced points for frictionally engaging a wall surface and a wall seam surface at an angle to each other, a portion of said strap being displaced to provide an opening through which a tool may be inserted and to provide a fulcrum on which said tool may be pivoted to distort said strap.
5. A cable or like support for insertion in a wall seam comprising a strap of spring material adapted when distorted to provide three points, for frictionally engaging a wall and wall seam surfaces which surfaces are at an angle to each other, and perforated between its ends and provided with an integral lug adjacent its perforation to permit insertion of a tool and provide a fulcrum therefor for further distortion to receive a cable or the like between the strap and the wall.
10. 3. A cable or like support for insertion in a wall seam comprising a strap of spring material adapted when distorted to provide three points, for frictionally engaging a wall and wall seam surfaces which surfaces are at an angle to each other, and perforated between its ends and provided with an integral lug adjacent its perforation to permit insertion of a tool and provide a fulcrum therefor for further distortion to receive a cable or the like between the strap and the wall.
15. 4. In a cable or like support for insertion in a wall seam, a spring having one end for insertion in the seam to be frictionally retained therein and having a perforated pro-
20. jection at a point spaced from said end, and an element having an end for insertion in the seam and retained by one face thereof and having its other end adapted to engage said perforated projection whereby said element is distorted so as to be held in assembly with said spring.
25. 5. In an article of the class described, a spring member having a portion for frictionally engaging opposing sides of a wall seam and having a body projecting from said portion to engage the exterior face of the wall, and an element below said member one end of which element is adapted to be inserted in said seam and be retained by said member portion and a face of the wall seam, and the other end of which element is adapted to be interengaged with the body of said member whereby said element is distorted so as to be held in position.
30. 35. 40. 45. In testimony whereof I hereunto affix my signature this 1st day of April, 1924.

PHILIP HOGAN.
